Primary Examiner — John Windmuller*Assistant Examiner* — Benjamin Weeks(74) *Attorney, Agent, or Firm* — McAndrews, Held & Malloy, Ltd.(57) **CLAIM**

The ornamental design for a medication container, as shown and described.

DESCRIPTION

FIG. 1 is a top, front, left side perspective view of a medication container showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a bottom, rear, right side perspective view thereof; and,

FIG. 9 is a top, front, left side perspective view thereof, including unclaimed features.

The broken lines of FIGS. 7 through 9 form no part of the presently claimed design.

1 Claim, 7 Drawing Sheets**US D804,806 S**
